DENTAL APPLIANCE

John Alfred Linde, Brooklyn, N. Y.

Application October 5, 1935, Serial No. 43,725
In Germany April 5, 1935

6 Claims. (Cl. 32—14)

This invention relates to dental devices and appliances, particularly of the type wherein one or more actuating members are attached to the arch wire or frame or the latter itself consists of two or more arch members which are held together by means of rings or annular clamps.

The main object of my invention is to provide dental appliances and devices of the character indicated which are altogether free from soldered, brazed or welded joints and connections between the parts making up the appliances or devices concerned.

Another important object of my invention is to utilize a main arch wire or frame and attach thereto various devices and actuating members for influencing individual teeth or groups thereof, by means which can be readily and speedily applied and fixed in position without the use of heat or any other such treatment.

20 A further object is to build up an arch wire or frame itself by means of separate arch members retained together by annular clamps or rings which may be tightly fixed upon the same without the use of any flux or type of solder.

25 It is also an object of the invention to provide devices for attachment to an arch wire or frame in the manner indicated, in the form of tapered members such as springs and clasps, which latter may also be adapted for attachment to each other.

Other objects and the various advantages accruing from the actual construction and use of my invention will appear more fully in detail as this specification proceeds.

30 In the accompanying drawing forming part hereof,

Fig. 1 illustrates by way of example, the major portion of a lingual arch wire or frame provided with a plurality of devices or members secured thereon by means and also themselves in great part embodying the principles of the invention.

Fig. 2 is a side view of a spring embodying certain features of the invention and forming one of the devices attached to the arch wire of Fig. 1, and being illustrated in initial form.

Fig. 3 is another view of the same spring.

Fig. 4 is a sectional view of a part or device of Fig. 1 on line IV—IV.

Fig. 5 is a sectional view of the arch wire or frame as well as a spring similar to the form shown in Figs. 2 and 3, and a clamping ring or sleeve on line V—V in Fig. 1.

Fig. 6 is a plan of a labial arch in position upon a row of teeth and in its own structure and in the manner of attachment of various dental members

or actuating devices thereto embodying the principles of the invention in practical form.

Fig. 7 is a view of a dental appliance having clasps which in their form and in their manner of mutual assemblage embody the main principles of the invention.

Fig. 8 is a side view of a tapered spring forming a device embodying certain of the principles of the present invention.

Fig. 9 is a plan view of the same spring.

Fig. 10 is an end view of the spring of Fig. 8.

Fig. 11 is a fragmentary view of an arch wire with part of a spring member shown as secured to the same by means of a clamp ring.

Fig. 12 is a modification of the parts shown in Fig. 11.

Fig. 13 is a further modification.

Fig. 14 is a still further modification.

Fig. 15 is an end view of the fragmentary parts of Fig. 12.

Fig. 16 is a partial plan view of a spring of Fig. 11.

Fig. 17 is a side view of the same spring.

Throughout the views, the same or duplicate parts are indicated by the same reference numerals.

It is common practice in the dental and orthodontic professions to use devices for straightening teeth from conditions of malocclusion, wherein a wire clip and one or more springs act against the teeth to be straightened, or else wires, etc., are used to engage the teeth with one end located in small tubes secured to metal bands surrounding the individual teeth involved. In these devices, the springs may be pivotally attached to the wire by means of sleeves soldered to the springs, or the springs are soldered to the wire. It is a well known fact that the making of such appliances, including the soldering of small parts and otherwise attaching the springs to sleeves, etc., requires a great deal of practice and skill, and is often very troublesome.

It must also be added that the heat necessary to soldering or brazing operations tends to more or less deprive the springs and even the arch wires of their characteristics, such as hardness, resiliency, rigidity and color.

Hence with the foregoing objects in view, and in order to depart altogether from above enumerated disadvantages heretofore prevalent in the art, the present invention does away with the use of soldering, brazing or any and all heating operations and treatments by means which will now be described in detail, due reference being had to the accompanying drawing.

In the practice of my invention, a lingual arch wire of known type consisting of two lingual arch members 1 and 2, retained in assembled relation by a sleeve 3 is provided with a plurality 5 of members for securing various appliances to said arch members, in the form of simple clamping rings or annular clamps 4, 4, etc. The said clamping rings are first passed over the arch member intended to be provided with an actuating 10 member to the desired position, and then a spring 5, for example, preferably tapered and flattened along one side, is thrust by its smaller end under the clamping ring which is to secure it, and the spring then forced through the space 15 between said ring and the arch member until the spring is firmly wedged in place and cannot be forced in further. In order to make certain that the spring will not turn or twist in any manner, the arch wire may be flattened along the outer 20 side. A fragmentary section of such arch wire is shown in Figs. 11 and 15, for example, the flat portion 49 mating with the flat side of a spring or member 50.

The spring 5 is also shown in Figs. 8, 9 and 10, 25 wherein it may be clearly seen that it is not only tapered, but also practically half round. When it is to be applied to an arch wire, it is preferably bent into desired shape as illustrated in Fig. 1, the full lines showing its form when free from 30 restraint, while it may assume a shape indicated at 6 or 7 when placed against a tooth which is to be gradually influenced and moved thereby.

A different actuating member is shown in the 35 form of a spring 8 in the first three views, the same tapering initially toward the ends and having at least one side flat along the entire length, except for a stop projection 11, while a locating projection 9 is disposed on the opposite side. A clamping ring 4, similar to that already mentioned is placed in position on either arch member 1 or 2, over a notch similar to 15 in the member involved after having first placed the spring 8 in position on the arch member so that its locating projection 9 fits into the notch, the 40 clamping ring being necessarily forced into position upon the spring until it is wedged thereon and abuts stop projection 11, when it will be found that the spring is fast on the arch member. The ends may be bent or doubled over and 45 the extremities as well, as indicated at 10, 10, a section through the doubled over portions being shown in Fig. 4, illustrating that the meeting sides are advantageously flat. At the right, upon arch member 2, the spring is shown with the one end 12 only slightly bent instead of being bent 50 double, this form being occasionally useful.

Instead of having the spring provided with a 55 projection engaging in a notch on the arch member, a slight modification of the clamping ring is feasible as indicated at 13, the same securing a resilient hook 16 in position on the arch member and being itself definitely located in desired position by having a portion 14 indented so as to project into a notch similar to notch 15 in the 60 arch. On the arch member 1 is slidably mounted a sleeve 17 having a row of one way teeth 19 which are engaged by the hooked end 18 of member 16, it being obvious that when the latter member is retained in fixed position on the arch 65 member, the hooked end 18 will prevent the sleeve 17 from entering further up on said member, but may be drawn toward the lower end thereof while the end 18 of the hooked member 16 slips over one after the other of teeth 19. Any attained position of sleeve 17 will thus be retained

by the hooked member and the teeth 19. Sleeve 17 may have an anchoring band 20 attached to the same in any manner known in the art, and is adapted to envelop a jaw tooth to anchor the arch wire as a whole.

At the upper right in Fig. 1, a clamping ring is indicated at 13, having its indentation 14 locating it by projecting into notch 15, the indicated ring retaining a reversed spring indicated at 21. The forms of springs and arch wires as well as other 10 actuating members just described are illustrative of certain uses of the clamping rings on lingual arch wires, but many other uses are possible.

In Fig. 6 a labial arch wire or frame is shown in a panoramic plan view as built up of several 15 members, as for example, of a relatively light and resilient member 21 having the ends thereof secured to a pair of heavier side wires or arch members 24, 24 by means of annular clamping members 23, 23. If found necessary, the intermediate 20 arch member 21 may be divided in the center and the two parts secured to each other by a clamping ring or member, although this is superfluous to illustrate as it is easily understood from what appears in Fig. 6. This lighter member 21, however, is provided with a plurality of individual 25 springs or actuating members similar to 26 which are attached by clamping rings 25, 25 and bear against the front teeth 27 of the teeth to be treated. These springs are introduced into position under their clamping members 25 from their pointed ends, and thereafter bent when in position to conform with the desired shapes or conditions to be met.

The opposite ends of the side wires 24, 24 are 30 preferably bent or shaped at 29, 29 and adapted, if desired to engage against the eye teeth 30, 30, respectively. At the other ends of said side wires sleeves 33, 33 are placed upon said members in 35 slidable relation, and have anchoring bands 34, 34 permanently secured thereto for anchoring the whole assemblage to the teeth 35, 35, while the sleeves are retained in proper position upon the arch wires by hooks 31, 31 engaging projections 40 32, 32 on said sleeves. The hooks are secured 45 upon the arch wires 24, 24 by clamping rings or members 28, 28, which are similar to rings 4, 23 or 25, except as to size. Rings 23 are naturally 50 larger than rings 28, as the ends 22 of arch wire 21 are somewhat larger than the ends of hooks 31.

The springs or fingers 26 have been stated to be 55 bent after being set in place upon the arch wire 21, and in Figs. 11, 13, 14, 12, 15, fragmentary sections of an arch wire are shown with a tapered spring retained in position by a clamping ring. In Figs. 11, 13 and 14, the part 48 of the arch wire has a flat side 49 against which a spring is held 60 by clamping ring 4, similar to rings 4 in Fig. 1. The spring 50 in Fig. 11 has the tapered end 51 wedged under the ring 4 and is bent transversely to the axis of arch wire 48, while in Fig. 13 the spring or finger 56 is similarly held, the tapered end 58 is bent transversely to arch wire 48 from an original position indicated at 57. The spring 65 or finger 59 in Fig. 14 is retained against flat side 49 of the arch wire and has both ends bent perpendicularly to said flat side, the smaller end 61 having in this case been cut off from an original length indicated at 60 after having been 70 bent upwardly from initial form indicated at 62. The two partial views of such springs or fingers as are used in Fig. 11 are also shown in initial form in Figs. 16 and 17, which are to some extent 75 also illustrative of the general form of the other

more tapered or pointed springs or fingers in the other views.

The fragmentary arch wire 52 of Figs. 12 and 15 has a spring or finger 53 tapered at 54 and secured to the wire by a clamping ring 13 similar to ring 13 of Fig. 1 and having its indented portion projecting into a notch not shown in wire 52 but similar to notch 15 in arch member 2 of said Fig. 1. The tapered end 54 may be bent downwardly at an angle as indicated at 55, if desired.

A third type of arch or appliance is illustrated in Fig. 7, the same being intended to be inserted in a gap between two spaced teeth occupy the place of missing teeth, the tapered clasps 36 and 38, for example being adapted to grip two such spaced teeth, and the other two tapered clasps 43 and 46 being adapted to clasp two corresponding spaced teeth on the other side of the same set of teeth. In order to render the distances between the clasps adjustable to suit various conditions, the clasps 36 and 46 have tapered shanks 37 and 45, respectively, which are secured to shanks 39 and 44 of clasps 38 and 43, respectively by means of annular clamps or rings 40 and 47. Upon shank 39 of clasp 38 is a fixed side projection 41 which is tapered and secured to a bar 42 rigid with shank 44 of clasp 43 by means of clamping ring 4. The tapered ends of the mentioned projections provide for wedging of the parts within the clamping rings or members while the relatively straight portions of shanks 39, 42 and 44 allow initial shifting or changing of the relative distances of the clasps from each other when the tapered ends of shanks 37, 41 and 45 have been initially inserted beneath rings 40, 4 and 47, respectively. This form of construction makes it possible to adjust the clasp appliance just described to various sizes of mouths and different spaces between teeth. It is then intended to secure replacement teeth upon the parts of the device between the clasps on each side, the bar or cross member 42 being curved to follow the shape of the roof of the mouth in which the appliance is to be located. The bar 42 may be disposed centrally between the clasps.

Manifestly, variations of my invention are possible and may be resorted to, while parts may be modified or used without others within the scope of the invention, and all such variations may be readily understood from the above description and accompanying illustration without further elaboration, as such structures will easily suggest themselves to those skilled in the art.

Having now fully described my invention, I claim:—

1. A dental appliance including a main elongated member forming a frame, means for anchoring the same to a holding tooth including a sleeve frictionally mounted upon said member and having an anchoring band secured

thereto and surrounding said tooth, a projection disposed upon said sleeve, a hooked member engaging said projection to retain the sleeve in predetermined position upon the elongated member, and means securing said hooked member upon said elongated member comprising a clamping ring retaining a portion of said hooked member in intimate wedged relation with said elongated member by enveloping both of said members.

2. A dental appliance including the combination, with a wire member forming part of a frame, there being a flattened side upon the same and a depression in the form of a notch in said flattened side, of an actuating device including an elongated spring of non-circular cross section having a portion of the same held against the flattened side of said wire member, a projection upon said spring extending into said notch in the flattened side of said wire member to definitely locate said spring in position on said wire, and a clamping ring surrounding both said wire member and said spring and frictionally retaining the two in assembled relation with the projection upon the spring located in the notch upon said wire.

3. A dental appliance according to claim 2, wherein the spring has a second projection forming a stop against which the clamping ring abuts so as to definitely locate the latter with respect to said spring and the wire member.

4. A dental appliance according to claim 2, wherein the spring is tapered toward both ends and the projection is located between the ends, and wherein said spring is also provided with a second projection between the ends thereof, serving as a stop abutment for the clamping ring.

5. A dental appliance according to claim 2, wherein the clamping ring has an indented or a depressed portion projecting into the notch in the wire member in order to definitely locate said clamping ring and the actuating device upon the wire member in predetermined accurate position.

6. A dental appliance including the combination, with a wire member forming part of a frame, there being a portion upon said wire member adapted to have an actuating device held against the same, said portion having a depression in the form of a notch therein, of an actuating device in the form of an elongated spring having an engagement portion on the same held against said portion upon said wire member, a projection upon said engagement portion of said device extending into the notch in the wire member serving to definitely locate said spring in position therein, and a clamping member surrounding both said wire member and said spring and frictionally retaining the two in assembled relation with the projection of the actuating device located in the notch upon the wire member.

JOHN ALFRED LINDE.
